HANDLE FOR BORE GAUGE

Otto C. Jelinek, Cranston, R.I., assignor to Federal Products Corporation, a corporation of Rhode Island

Filed Nov. 3, 1966, Ser. No. 4,541

Term of patent 14 years

(Cl. D52—6)

FIG. 1

FIG. 2

FIG. 3

FIG. 4

FIG. 5

FIG. 6

FIG. 1 is a perspective view of a handle for bore gauge showing my new design;

FIG. 2 is a top view thereof;

FIG. 3 is a side elevational view thereof;

FIG. 4 is a bottom view thereof;

FIG. 5 is an end view taken from the righthand side of FIG. 2;

FIG. 6 is an end view taken from the lefthand side of FIG. 2.

The dominant features of my design reside in the portions shown in full lines.

The undisclosed side of the handle is a mirror image of the side shown in FIGS. 1 and 3. The measuring end of the bore gauge, shown for illustrative purposes in FIGS. 1-4, is either broken away or omitted in some of the views for ease of illustration.

1 claim:

The ornamental design for a handle for bore gauge, substantially as shown and described.
